(57) **CLAIM**

The ornamental design for a luggage wheel assembly, as
shown and described.

DESCRIPTION

FIG. 1 is a back left perspective view of a luggage wheel
assembly of our new design;

FIG. 2 is a second back left perspective view of the luggage
wheel assembly;

FIG. 3 is a rear view of the luggage wheel assembly of FIG.
2;

FIG. 4 is a front view of the luggage wheel assembly of FIG.
2;

FIG. 5 is a right side view of the luggage wheel assembly of
FIG. 2;

FIG. 6 is a left side view of the luggage wheel assembly of
FIG. 2;

FIG. 7 is a top view of the luggage wheel assembly of FIG.
2; and,

FIG. 8 is a bottom view of the luggage wheel assembly of
FIG. 2.

The broken lines in the drawings illustrate environmental
subject matter that forms no part of the claimed design.

1 Claim, 5 Drawing Sheets
